US00D930476S

(12) **United States Design Patent** (10) **Patent No.:** **US D930,476 S**
Bontrager et al. (45) **Date of Patent:** **** Sep. 14, 2021**

(54) **CAP FOR A BEVERAGE KEG**

(71) Applicant: **Zume, Inc.**, Camarillo, CA (US)
(72) Inventors: **Rick Bontrager**, Mountain View, CA (US); **Randall Strange**, Manteca, CA (US)

(73) Assignee: **Zume, Inc.**, Camarillo, CA (US)

(**) Term: **15 Years**

(21) Appl. No.: **29/711,040**

(22) Filed: **Oct. 28, 2019**

(51) **LOC (13) Cl.** **09-07**

(52) **U.S. Cl.**

USPC **D9/454**

(58) **Field of Classification Search**

(57) **CLAIM**

The ornamental design for a cap for a beverage keg, as shown and described.

DESCRIPTION

FIG. 1 is a top perspective view of a cap for a beverage keg showing my new design;

FIG. 2 is a bottom perspective view of the cap for a beverage keg of FIG. 1.

FIG. 3 is a front view of the cap for a beverage keg of FIG. 1.

FIG. 4 is a back view of the cap for a beverage keg of FIG. 1.

FIG. 5 is a right side view of the cap for a beverage keg of FIG. 1.

FIG. 6 is a left side view of the cap for a beverage keg of FIG. 1.

FIG. 7 is a top view of the cap for a beverage keg of FIG. 1; and,

FIG. 8 is a bottom view of the cap for a beverage keg of FIG. 1.

1 Claim, 6 Drawing Sheets
